ELECTRIC SWITCH.

Application filed January 23, 1925. Serial No. 4,156.

This invention relates to electric switches and more especially to electric switches adapted for use in incandescent lamp sockets.

The invention has for an object to provide a switch mechanism which has quick make and break movements and which is of simple, strong and durable construction and easy to assemble and repair.

A feature of the invention is the making of the insulating support for the contact elements in two separable sections which are held together by a single centrally disposed bolt and on one of which the movable contact element is mounted at one side of such bolt; one or more stationary contacts being mounted on the other of the separable sections of the insulating support.

The movable contact element and its actuating means are preferably initially assembled on the side wall of a metal angle bracket which latter and parts carried thereby may be easily mounted as a unit in a channelway in one of the sections of the insulating support. In a similar channelway in the mating section of the insulating support, one or preferably two stationary contact elements are mounted, in spaced relation and in position to be engaged or bridged by the movable contact element. The parts of the switch mechanism are thus rendered readily accessible, making it an easy matter to assemble or disassemble the device.

In the accompanying drawings, Fig. 1 is a longitudinal sectional view of an incandescent lamp socket embodying the invention. Fig. 2 is an elevation of the socket insides looking into one end of the channelway through the insulating support. Fig. 3 is a top plan view of the lower section of the insulating support showing the stationary contact elements mounted thereon. Fig. 4 is a reverse or bottom plan view of the parts shown in Figs. 2 and 3. Fig. 5 is a bottom plan view of the upper section of the insulating support showing the movable contact element and its operating mechanism. Figs. 6, 7, 8 and 9 are detail perspective views of the several parts of the switch mechanism.

While the present switch mechanism is adapted for many uses, it is shown as embodied in a lamp socket only. Referring to the drawings, 1 represents the socket shell, 2 the cap and 3 the lining, within which is

disposed the socket insides comprising the insulating support which is preferably moulded in two mating sections 4, 5, from a suitable insulating material such as bakelite. A central bolt 6 may have its headed end 7 imbedded by moulding in the lower section 5; the other end of such bolt being threaded to receive the nut 8 which holds the sections 4 and 5 in assembled relation. To insure against a relative rotary shift of the sections 4 and 5, one of them may be formed with projections 9 which enter corresponding depressions 10 in the other section.

The section 4 of the insulating support is formed with a transverse channelway 11 in which is mounted the sheet-metal bracket 12 carrying the movable contact element 13 and its actuating mechanism. The bracket 12 has an angular foot portion 14 which is secured to the bottom wall of the channelway 11, Fig. 5, by means of screws 15. It also is formed with two stop-elements 15, Fig. 6, and a hole 16 in which is riveted the pivot pin 17.

Disposed flatwise against the bracket 12 is the arm 18, Fig. 7, of which the movable contact element 13 is an integral part; the element 13 being in the form of a tongue bent to stand at an angle to the plane of the arm 18. The arm 18 has a pivot hole 19 and an end lip 20 formed with an aperture 21 through which extends one extremity of the bar 22, the other end of which is pivotally connected at 23 to the operating lever 24 which latter is pivoted on the pin 17 and is separated from the arm 18 by a washer 25, Fig. 5, equal in thickness to the bar 22. The bar 22 is surrounded by a coil spring 26 the ends of which press, respectively, against the lip 20 on the carrier 18 and shoulders 27, Fig. 9, on the bar 22. The operating lever 24 is formed with oppositely directed stop arms 28 which engage the stationary stops 15 on the bracket 12 to limit the movement of such lever in opposite directions.

It will be understood that the lever 24, bar 22, spring 26 and arm 18 form a toggle device and that the spring operates to snap the arm 18 quickly from one of its extreme positions to the other when, in the movement of the operating lever, the pivot 23 crosses alignment with the pivot 17 and aperture 21.

The section 5 of the insulating support is

formed with a transverse channelway 29, similar to the channelway 11 in the section 4. In the bottom of the channelway 29 are secured the stationary contact springs 30, 5 31. The contact 30 is electrically connected to the terminal screw 32, Fig. 3, while the contact 31 is connected to the usual spring-pin contact element 33. The remaining terminal screw 34 is connected directly to the 10 other spring-pin contact element 35.

In one extreme position of the arm 18, the movable contact 13 is retracted from the stationary contacts 30, 31, as shown in full lines, Fig. 2, and the circuit is open. In the 15 other extreme position of the contact member 13, shown in dotted lines, Fig. 2, it electrically bridges the gap between the contacts 30, 31, and thus closes the circuit.

The handle of the operating lever may be 20 provided with a moulded knob 36 of suitable insulating material.

The contact member 30 is preferably made longer and more springy than the contact member 31 and is so bent as to be engaged 25 by the movable contact member 13, in the circuit closing movement of the latter, before the stiffer contact member 31 is engaged. This provision insures the continued making of efficient electrical contact after 30 long periods of use and avoids the necessity of using extreme care in adjusting the contacts when assembling the device.

Having thus set forth the nature of the invention, what I claim herein is—

1. An electric switch comprising a cylindrical insulating support split transversely of its axis into two separable sections the meeting faces of which are formed with registering channelways, a centrally disposed bolt for holding said sections in assembled relation, an angle bracket having its bottom portion secured to the bottom wall of the channelway in one of said sections, stationary contact means mounted in the channelway in the other section, and a spring-toggle-operated movable contact mechanism mounted on the side portion of said angle bracket at one side of said bolt and including a movable contact element adapted to engage the stationary contact means. 50

2. In an electric switch mechanism, a pair of spaced stationary contact members, a spring-toggle-operated bridging contact member adapted to press in substantially the same direction upon each of said stationary contact members, one of said stationary contact members being longer than the other and in the form of a leaf spring arranged to be engaged first by the movable contact member in the circuit closing movement of the latter. 55

In testimony whereof, I have signed my name to this specification.

DANIEL H. CHASON.
